UNITED STATES PATENT OFFICE.

JAMES B. HAMILTON, OF HOBOKEN, AND ALSTON HAMILTON, OF SANDY HOOK, NEW JERSEY.

FIREARM.

1,269,178.

Specification of Letters Patent. Patented June 11, 1918.

Application filed May 3, 1916, Serial No. 95,287. Renewed November 6, 1917. Serial No. 200,643.

To all whom it may concern:

Be it known that we, JAMES B. HAMILTON and ALSTON HAMILTON, citizens of the United States, and residents, respectively, of 5 Hoboken, in the county of Hudson and State of New Jersey, and of Sandy Hook, in the county of Monmouth and State of New Jersey, have invented a new and useful Improvement in Firearms, of which the following is a specification.

Our invention relates to improvements in firearms and is particularly adapted to fire arms, such as shoulder arms and machine guns.

15 The object of our invention is to provide a depressed stock for firearms so as to bring the head of the operator into a protected position, an altiscopic sighting tube being employed.

20 Means are provided to adjust the sighting tube for a given range of the firearm so that the firearm will be brought automatically to the proper elevation for that particular range when the operator brings the 25 object into view through the sighting tube. This permits the elimination of the usual sights on the gun barrel.

Means are also employed for removably attaching the altiscopic sighting tube to the 30 stock so that the sighting tube may be readily removed and replaced.

A practical embodiment of our invention is represented in the accompanying drawings, in which—

35 Figure 1 represents a firearm in side elevation with our improvements applied thereto, the sighting tube being shown in full lines in its adjustment for the longest effective range of the firearm and the front 40 end of the sighting tube being shown in dotted lines adjusted to the "point blank" range of the firearm.

Fig. 2 represents an enlarged vertical longitudinal section through the parts embodying our invention.

45 Fig. 3 represents a detail section taken in the plane of the line III—III of Fig. 2,

Fig. 4 represents a transverse section taken in the plane of the line IV—IV of Fig. 2,

50 Fig. 5 represents a transverse section taken in the plane of the line V—V of Fig. 2, and

Fig. 6 represents a detail transverse section taken in the plane of the line VI—VI of Fig. 2.

55 The barrel 1 and its loading and firing

mechanisms may be of any well known or approved form.

A depressed stock 2 is secured rigidly to the barrel 1 by screws or other suitable fastening means 3. The depressed stock 60 may be provided with the front and rear hand grips 4 and 5, for facilitating the handling of the firearm.

The altiscopic sighting tube 6 is provided at its inner end with the oppositely arranged 65 threaded trunnions 7, 8, engaged by clamping screws 9, 10, for removably hinging the sighting tube to the stock casing. The altiscopic sighting tube is provided with an eye piece 11 at its inner end and its outer 70 end 12, extends forwardly along the firearm at a point above the barrel 1, the intermediate portion of the tube extending diagonally upward and forward along the top of the stock casing. The free or front end of 75 the sighting tube is swung to different positions for different ranges by the following mechanism: A cross shaft 13 is suitably mounted in the stock casing, which shaft is provided at one side of the stock with an 80 operating hand wheel 14. Within the stock casing, the shaft 13 is provided with a bevel gear 15 which meshes with a bevel gear 16 carried by a rotary shaft 17 mounted in suitable bearings within the stock casing and 85 extending upwardly and forwardly. This shaft 17 is also provided with a bevel gear 18 which meshes with a bevel gear 19 carried by a rotary shaft 20 also mounted in the stock casing and extending upwardly 90 and rearwardly. This shaft 20 is provided with a screw 21 which engages the screw threaded socket 22 of a bar 23 slidably mounted within the stock casing. This bar has a yoke 24 which embraces the sighting 95 tube 6 and this yoke is connected to the sighting tube by means of a pin and slot connection 25, 26, the slots being elongated in the direction of the length of the sighting tube to permit the bar 23 in its longitudinal 100 movements to swing the sighting tube.

The mechanism above described permits of a very rapid and accurate adjustment of the sighting tube to different ranges.

To enable the operator of the firearm to 105 elevate the barrel of the gun to the proper position for firing at an object at a certain given range without the use of other sights than the sighting tube itself, we provide a fixed range scale 27 on the side of the stock 110

casing, along which scale a pointer 28 is fitted to travel. The pointer 28 is fixed to the gear 29 loosely mounted on the hand wheel shaft 13. This gear 29 meshes with a gear 30 carried by a shaft 31 mounted in the stock casing and this shaft 31 is provided with a toothed segment 32 which meshes with a gear 33 fixed to the hand wheel shaft 13. The relative movement of the range 10 scale pointer 28 and the sighting tube, is such that when the pointer 28 is moved by the operation of the hand wheel 14 to a given range indicated on the scale 27, the sighting tube will be moved to such a position that when the operator brings the object at such given range into view through the sighting tube, the barrel of the firearm will be elevated to the proper position for accurate firing at such given object.

36 Means are provided for securing the sighting tube rigidly in position at any given range, which means is herein shown as comprising the following elements: Two lugs 34, 35, carried by the sighting tube 6 project downwardly into the stock casing between the arms of clamps 36, 37, which clamps are provided with ends 38, 39, the end 39 having a screw threaded engagement with a cross bolt 40 suitably mounted in the stock casing and provided, exterior to the stock, with a handle 41 for turning the bolt. The turning of the bolt in one direction will clamp the lugs 34, 35, rigidly to the stock and the turning of the bolt in the opposite direction will release these lugs. It is desirable that the handle 41 be located upon the opposite side of the stock from the hand wheel 14 for ready manipulation of the parts.

40 It will be seen that the sighting tube can be readily removed from the stock by unclamping the two at the lugs 34, 35, at the pin and slot connection 25, 26, and at the trunnions 7 and 8.

45 While we have shown the sighting tube as separable, so that the upper portion of the sighting tube can be replaced if shot away or otherwise put out of commission, it is to be understood that the sighting tube 50 may be made in any number of parts.

The depressed stock and its altiscopic sighting tube may be readily applied to a firearm having any loading and firing mechanism, either while in course of manufacture or afterward, as may be necessary, thus rendering such firearm suitable for use where the same is to be used behind a parapet, an embankment, armor plate, or other obstruction whereby the head of the user can be protected while the barrel is in its proper position for firing over said obstruction.

In use, the operator of the firearm is given the range of the object to be fired at. He immediately turns his hand wheel 14 to 65 bring the pointer 28 to the given range on

the scale 27. This movement, at the same time, will swing the altiscopic sighting tube to its proper angular position with respect to the barrel of the firearm. The tube may then be locked rigidly to the stock in this 70 adjusted position by tightening the handle 41. The operator then finds the object through the sighting tube. When the object has been found, the barrel will have been automatically elevated to the proper 75 position for firing at such object at the given range.

It is obvious that changes may be resorted to in the form, construction and arrangement of the several parts without departing 80 from the spirit and scope of our invention; and hence we do not wish to limit ourselves strictly to the structure herein shown and described.

What we claim is:—

1. A firearm having a depressed stock and an altiscopic sighting tube hinged at its rear end to the stock and adjustable to different ranges.

2. A firearm having a depressed stock and a removable altiscopic sighting tube hinged at its rear end to the stock and adjustable to different ranges.

3. A firearm having a depressed stock and an altiscopic sighting tube hinged at its rear end to the stock and adjustable to different ranges and means for securing the sighting tube to the stock in its different adjustments.

4. A firearm having a depressed stock and a removable altiscopic sighting tube hinged at its rear end to the stock and adjustable to different ranges and means for securing the sighting tube to the stock in its different adjustments.

5. A firearm having a depressed stock, an altiscopic sighting tube hinged at its rear end to the stock and means carried by the stock for raising and lowering the front end of the sighting tube to adjust it to different ranges.

6. A firearm having a depressed stock, a removable altiscopic sighting tube hinged at its rear end to the stock and means carried by the stock for raising and lowering the front end of the sighting tube to adjust it to different ranges.

7. A firearm having a depressed stock, an altiscopic sighting tube hinged at its rear end to the stock, means carried by the stock for raising and lowering the front end of the sighting tube to adjust it to different ranges, and means for securing the sighting tube to the stock in its different adjustments.

8. A firearm having a depressed stock, a removable altiscopic sighting tube hinged at its rear end to the stock, means carried by the stock for raising and lowering the front end of the sighting tube to adjust it to different ranges, and means for securing the 125

sighting tube to the stock in its different adjustments.

9. A firearm having a depressed stock and its casing, an altiscopic sighting tube hinged thereto and adjustable to different ranges and means for adjusting the sighting tube comprising a train of gears within the casing and an operating hand wheel at the side of the casing.

10. 10. A firearm having a depressed stock and its casing, an altiscopic sighting tube hinged thereto and adjustable to different

ranges, a range indicator and a common means for operating the indicator and adjusting the sighting tube comprising trains 15 of interconnected gears within the casing and an operating hand wheel at the side of the casing.

In testimony that we claim the foregoing as our invention, we have signed our names 20 this 1st day of May, 1916.

JAMES B. HAMILTON.
ALSTON HAMILTON.
